UNITED STATES PATENT OFFICE.

ALBERT J. ROSS, OF RUBICON, MICHIGAN.

ENGINE CYLINDER AND PISTON.

Application filed February 28, 1924. Serial No. 695,782.

To all whom it may concern:

Be it known that I, ALBERT J. Ross, a citizen of the United States, residing at Rubicon, in the county of Ontonagon and State 5 of Michigan, have invented certain new and useful Improvements in an Engine Cylinder and Piston, of which the following is a specification.

This invention relates to new and useful 10 improvements in internal combustion engines and more particularly to the cylinder and piston construction thereof.

One of the principal objects of the present 15 invention is to provide a cylinder and piston construction, which will be very efficient in operation, and of such construction, as to prevent the carbonization of the inner wall of the cylinder.

Another object of the present invention is 20 to provide a cylinder and piston construction of the above mentioned character, wherein the same are substantially angular in cross section, pairs of oppositely arranged piston rings being provided and adapted to engage 25 the respective walls of the cylinder.

Another important object of the present 30 invention is to provide a device of the above mentioned character, which is simple in construction, inexpensive, strong and durable, and further well adapted for the purposes for which it is designed.

Other objects and advantages of this invention will become apparent during the course of the following description.

In the accompanying drawing, forming a 35 part of this specification, and in which like numerals designate corresponding parts throughout the same:

Figure 1 is a vertical section through a 40 cylinder showing the piston mounted therein, in side elevation.

Figure 2 is a transverse section, taken on the line 2—2 of Figure 1.

Figure 3 is a transverse section through the piston, showing the piston rings in plan elevation.

Figure 4 is a side elevation of one of the units of the piston ring.

Figure 5 is a front elevation thereof.

In the drawing, wherein for the purpose of illustration is shown the preferred embodiment of my invention:

The numeral 1 designates the outer wall of the cylinder, designated generally by the numeral A, and the inner wall 2 is spaced therefrom in a manner shown at 3,

to provide a water jacket. The purpose of this construction is well known in the art, and it is not thought necessary to further go in detail relative to the same.

The outer walls of the cylinder A are preferably rectangular. The outer faces of the inner wall 2 of the cylinder are also rectangular in design. The inner walls of the faces 2 are substantially rectangular in cross section, and at each of the corners thereof, a bevelled face is provided, such as is illustrated at 4 in the drawing. It will thus be seen that a cylinder has been constructed which is substantially angular in cross section for the purposes hereinafter set forth and described.

Operating within the cylinder A in the usual manner is the piston 5. The latter is substantially of the same shape as the inner walls of the cylinder, and also angular in cross section, for cooperation with the faces of inner wall 2 of the cylinder A. The corner of the outer faces of the piston 5 are also bevelled as shown at 6 in the drawing, to conform to the shape of the bevelled portion 4 of the cylinder.

Formed in the outer faces of the walls of the piston 5, and extending circumferentially therearound, are the grooves or channels 7. The purpose of providing the grooves 7 is to receive the piston rings which are supported therein, and the piston rings in the present invention comprise the plurality of units each of which are of the same construction and the same is clearly shown in Figures 4 and 5 of the drawing. Each unit 8 is in the form of a substantially long strip of metal and has its ends slotted with the cut-away portions 9 for a purpose to be presently described. The end portions 10 of each of the strips 8 are also provided with the bevelled edges 11 in the manner as shown in Figures 3 and 5 of the drawings.

In position, the strips or units 8 are placed in the channels formed in the piston 5, in such a manner as to have the strips arranged in pairs. In this manner, it will be readily seen that the ends of one of the pair of strips will overlap the ends of the oppositely arranged pair of strips, so that the end portions 10 of the adjacent strip will have their bevelled portions 11 in alignment when the ends 10 are arranged in overlapping engagement in the manner as clearly shown in Figure 3 of the drawings.

Adapted to be disposed between the rear

faces of each of the strips 8 and the respective sides of the piston 5 are the resilient springs 12. The purpose of these springs 12 is to provide a means for normally urging 5 the opposed pairs of strips 8 which form the piston rings into engagement with the inner faces of the inner wall 2 of the cylinder, in such a manner as to have the outer faces of the strips engaging the straight 10 faces of the cylinder and the bevelled portions of the overlapping strips operating with the bevelled faces 4 of the cylinder, whereby the piston will fit snugly in the cylinder in engagement with all of the inner 15 faces of the inner wall thereof and will prevent the loss of compression or the leakage of oil past the piston into the cylinder.

The simplicity of my device enables the same to be readily disassembled whenever necessary, and is of such a construction as to insure the efficient operation of the same, and will not only be strong, but also durable, thus prolonging the length of use of the cylinder and the piston.

20 While I have shown the preferred embodiment of my invention, it is to be understood that various changes in the shape, 25

size, and arrangement of parts may be resorted to, without departing from the spirit of the invention and the scope of the ap- 30 pended claim.

Having thus described my invention, what I claim is:

In combination with a cylinder having plane rectangularly disposed side wall surfaces with intervening planes, and rectangularly disposed corner wall surfaces, a piston fitting snugly within said surfaces and having a continuous ring groove, the inner wall of which is composed of plane rectangularly disposed wall sections, a ring composed of sections of the same shape and dimension, each ring section having a straight outer edge and bevelled end edges adapted to bear against the wall surfaces of the cylinder, the bevelled end portions of the ring sections overlapping each other, said ring section being received in the ring groove and 40 springs interposed between the ring section and the inner wall section of the groove. 45

In testimony whereof I affix my signature.

ALBERT J. ROSS.
